Lumenmax Reflector, image post date 2009, site visited Aug. 9, 2015, (online), <<http://www.ehydroponics.com/?action=product&id=3275&cid=1>>.*Primary Examiner — Kevin Rudzinski*Assistant Examiner* — Sean D Lough(74) *Attorney, Agent, or Firm* — Sheridan Ross PC(57) **CLAIM**

The ornamental design for a reflector, as shown and described.

DESCRIPTION

FIG. 1 is a first top perspective view of the reflector;
 FIG. 2 is a second top perspective view of the reflector;
 FIG. 3 is a bottom plan view of the reflector;
 FIG. 4 is a first bottom perspective view of the reflector;
 FIG. 5 is a second bottom perspective view of the reflector;
 and,
 FIG. 6 is a third bottom perspective view of the reflector.
 The broken lines where present in all Figs. illustrate portions of the reflector that form no part of the claimed design.
